UNITED STATES PATENT OFFICE.

GERHARD F. DROUVÉ, OF BRIDGEPORT, CONNECTICUT.

SKYLIGHT.

No. 892,034.

Specification of Letters Patent. Patented June 30, 1908.

Application filed January 29, 1908. Serial No. 413,256.

To all whom it may concern:

Be it known that I, GERHARD F. DROUVÉ, a citizen of the United States, and a resident of Bridgeport, in the county of Fairfield and State of Connecticut, have invented certain new and useful Improvements in Skylights, of which the following is a specification.

My invention relates to an improvement in sky lights, and particularly to the manner of supporting the same.

To enable others to understand my invention, reference is had to the accompanying drawings in which:

Figure 1 represents a broken view partly in section of a sky light construction and broken view of my improved clip attachment thereto; Fig. 2 is a broken side elevation of one of the channel irons of the sky light construction and end elevation of the iron purlins and clips; Fig. 3 is a broken perspective view of the channel irons and clips attached thereto; Fig. 4 is a detail broken view in perspective of one of the clips and its brackets; and Fig. 5 is a modified construction of one of the clips in cross section and broken view of a channel-iron.

Each of the channel irons 1 carry the mechanism for supporting the glass roof 2, and while this mechanism forms no part of my present invention, a brief description of the same will more clearly illustrate the advantage of my improvement.

3 is one of the supports adapted to be secured in each of the several channel-irons that form the roof structure.

4 are felt packings above and below the glass 2.

5 is one of a series of bolts anchored in the support 3.

6 is a sheet metal inverted U-shaped bar or cap parallel with the support 3 and U-shaped channel-iron 1 and resting on a shoudered portion of the bolt and is held in place by the nut 7.

8 is a spring lying between the cap 6 and plate 9 for holding the edges of the glass in place.

Heretofore, in putting up the sky light structure, the purlins 10, having been properly set, the channel-irons 1 were laid upon the girders a suitable distance apart for supporting the edges of the glass and, when so located, holes were drilled by hand through the channel-irons and purlins to receive the bolts by which the two were held together. This

method of erecting the structure was not only inconvenient in that the drilling had to be done with an ordinary hand tool and oftentimes in almost inaccessible places, but it also added greatly to the cost. 60

With my improved method of construction, I employ the sheet metal U-shaped clips 11 (Fig. 4) and secure thereto the brackets 12 by means of the rivets 13. The holes (not shown) in the clips for these rivets 65 are drilled in the shop by power and the brackets secured at once to the clips, each pair of brackets being set the proper distance apart to establish the position to be occupied by the channel-irons. The holes 14 70 are also formed in the upper leg of the brackets to register with holes (not shown) in each side of the channel-irons.

All the preliminary work, such as drilling the holes in the several parts and securing the 75 brackets 12 to the clips 11 having been done in the shop where the tools and other appliances are readily accessible, the assembling or putting together of the various parts on the job is a very simple matter. After the 80 purlins 10 are properly set, the clips are slipped over one leg of the purlins, as shown at Fig. 2, and the channel-irons are dropped between the pairs of brackets, as shown at Fig. 3, and secured to said brackets by the 85 bolts 15, seen also at Fig. 1. As the clips are not secured to the purlins by bolts, they can be easily moved longitudinally or transversely a distance sufficient to cause the 90 holes in the upper leg of the brackets and the sides of the channel-irons to register for the insertion of the bolts.

To prevent accidental shifting of the clips by the action of the wind or from any other cause, the end clip 11^a and its purlin 10^a 95 may be reversed, as shown at Fig. 2. This will effectually prevent shifting of the structure in the direction of arrow a, while the other clips will prevent shifting in the direction of arrow b. While this arrangement is 100 adapted for a horizontal construction, it is particularly adapted for the angular arrangement shown at Fig. 2.

The shape of the clips will, of course, be determined by the shape of the purlins with which they engage. In Fig. 5, 10^b represents a wooden purlin, and the retaining clip is represented by the metal strip 11^b, having the downward projecting holding lip 11^c embracing the corner of the purlin. 110

Having thus described my invention, what I claim as new and desire to secure by Letters Patent is:—

1. In a sky-light construction of the character described, the combination with channel-irons adapted to uphold the glass supporting mechanism, and the supporting purlins for said channel-irons, of retaining clips adapted to embrace said purlins and of sufficient length to support a plurality of the channel-irons, means for securing the channel-irons to the clips, for the purpose set forth.
2. In a sky-light construction of the character described, the combination with channel-irons adapted to uphold the glass support-

ing mechanism, and the supporting purlins for said channel-irons, of retaining clips secured to the channel-irons and adapted to embrace said purlins, said clips of sufficient length to support a plurality of the channel-irons so that said channel-irons can be arranged and maintained in parallel relation with each other, for the purpose set forth.

Signed at Bridgeport in the county of Fairfield and State of Connecticut this 18 day of January A. D. 1908.

GERHARD F. DROUVÉ.
